(57) **ABSTRACT**

Potassium carbonate, Cocoglucoside, a Preservative, Sodium gluconate, and Demineralized water. The formulation is intended to be dispensed and/or applied from a spray bottle or wet wipe. Demineralized water is used as a solvent and has a concentration of approximately up to approximately 99 percent of the weight by percentage. Potassium carbonate is the uric acid remover, and has a concentration of approximately 1-25 percent of the formulation. Cocoglucoside or Coco Glucoside is a natural, non-ionic, surfactant and acts as a cleaner and has a concentration of approximately 0.1-15 percent. Sodium gluconate is used as a chelating agent and has a concentration of approximately 0.1-25 percent. A chemical preservative may be added the formulation in any amount or percentage as desired or in any amount or sufficient quantity desired for the preservation or shelf life of the product.

TECHNICAL FIELD OF THE INVENTION

The present invention relates in general to automotive finishes. More specifically, the present invention relates to an automotive finish formulation for specifically neutralizing bird dropping and other acidic environmental hazards.

BACKGROUND OF THE INVENTION

Bird droppings can be extremely damaging to a car's paint job. If left untreated, bird droppings can penetrate a car's clear coat protective layer. Bird droppings have acid and can burn through the clear coat as quick as two days. Waiting too long to remove bird droppings can burn the clear coat and paint surface all the way to the metal.

Damage from bird droppings increases when it's hot outside because the droppings can warm up and harden on the paint. The sight of a car's clear coat protective layer being etched by bird droppings is not only the result of the corrosive property of the dropping. Damage also results from the car's clear coat protective layer contracting upon cooling to the uneven texture of the hardened deposit.

As paint lacquer warms during the day, it softens and expands. At the same time, that heat dries and hardens any bird droppings on the surface, as the paint lacquer cools overnight, it contracts, hardens around the texture of the bird dropping.

Bugs, meanwhile, interact in a similar way with paint. They also have chemicals that can eat through the clear coat and cause damage. Bugs can collect by the dozens on cars, especially during long highway trips.

The clear coat will eventually start to lift at different points where the clear coat has been damaged. Once the clear coat starts lifting, there's really no way to stop it.

Wax and polish treatments that protect against chemical attack from acid rain and UV sun damage provide limited protection from the paint expanding and contracting around bird droppings and the chemical interaction between the dropping and the car's clear coat, although they will make them easier to remove.

While it is recommended to wash a car once a week to remove droppings and bugs; this is often impractical for many car owners. Therefore it is recommended to keep a bottle of water and a microfiber rag in the car to quickly wipe away animal waste and other debris.

While water moistens a bird dropping and makes it easier to remove and may eliminate the damage from the physical heating and cooling of the dropping, water does nothing to neutralize the chemical effects associated with bird droppings or bugs.

Therefore, what is needed is a formulation or solution to replace the water commonly used on such wipes with a formulation that will neutralized the chemicals in bird droppings and bugs to stop or eliminate chemical interactions between droppings, bugs, and a car's clear coat.

Definitions

“Bases” are substances that, in aqueous solution, are slippery to the touch, taste astringent, change the color of indicators (e.g., turn red litmus paper blue), react with acids to form salts, promote certain chemical reactions (base catalysis), accept protons from any proton donor, and/or contain completely or partially displaceable OH⁻ ions. Examples of bases are the hydroxides of the alkali metals and alkaline earth metals (NaOH, Ca(OH)₂, etc.). Bases can be thought of as the chemical opposite of acids. Bases and acids are seen as opposites because the effect of an acid is to increase the hydronium (H₃O⁺) concentration in water, whereas bases reduce this concentration. The notion of a base as a concept in chemistry was first introduced by the French chemist Guillaume Francois Rouelle in 1754. He noted that acids, which at that time were mostly volatile liquids (like acetic acid), turned into solid salts only when combined with specific substances. Rouelle considered that such a substance serves as a “base” for the salt, giving the salt a “concrete or solid form”.

“Chelation” is a type of bonding of ions and molecules to metal ions. It involves the formation or presence of two or more separate coordinate bonds between a polydentate (multiple bonded) ligand and a single central atom. Usually these ligands are organic compounds, and are called chelates, chelators, chelating agents, or sequestering agents.

A “Chelating Agent” is a substance which combines with a metallic ion to produce an inert chelate.

“Hydroxide” is a diatomic anion with chemical formula OH⁻. It consists of an oxygen and hydrogen atom held together by a covalent bond, and carries a negative electric charge. It is an important but usually minor constituent of water. It functions as a base, a ligand, a nucleophile and a catalyst. The hydroxide ion forms salts, some of which dissociate in aqueous solution, liberating solvated hydroxide ions. A hydroxide attached to a strongly electropositive center may itself ionize, liberating a hydrogen cation (H⁺), making the parent compound an acid. Many inorganic substances which bear the word “hydroxide” in their names are not ionic compounds of the hydroxide ion, but covalent compounds which contain hydroxyl groups.

“Neutralization” is a reaction between an acid and base. In a neutralization reaction, an aqueous solution of a base reacts with an aqueous solution of an acid to produce a solution of water and salt in which the salt separates into its component ions. If the aqueous solution is saturated with a given salt solute, any additional such salt precipitates out of the solution.

SUMMARY OF THE INVENTION

The present invention is an automotive finish protection formulation. The formulation is comprised of the following compounds: Potassium carbonate, Cocoglycoside, a Preservative, Sodium gluconate, and Demineralized water. The formulation of the present invention is intended to be dispensed and/or applied from a spray bottle or wet wipe.

Demineralized water is used as a solvent and has a concentration of approximately up to approximately 99 percent of the weight by percentage. Potassium carbonate is

the uric acid remover, and has a concentration of approximately 1-25 percent of the formulation. Cocoglucoside or Coco Glucoside is a natural, non-ionic, surfactant and acts as a cleaner and has a concentration of approximately 0.1-15 percent. Sodium gluconate is used as a chelating agent and has a concentration of approximately 0.1-25 percent.

A chemical preservative may be added the formulation in any amount or percentage as desired or in any amount or sufficient quantity desired for the preservation or shelf life of the product.

In an alternative embodiment Decyl Glucoside, and additional can be added to the formulation in the same percentage as the Cocoglucoside cleaner, 0.1-15 percent. In yet another alternative embodiment, Cocoglucoside can be substituted with Cocobetaine in the same percentage of 0.1-15 percent.

BRIEF DESCRIPTION OF THE DRAWINGS

The accompanying drawings, which are incorporated herein and form a part of the specification, illustrate the present invention and, together with the description, further explain the principles of the invention and to enable a person skilled in the pertinent art to make and use the invention.

FIG. 1 is a table that illustrates the formulation of the present invention.

FIG. 2 is a table that illustrates an alternative embodiment formulation containing an additional natural cleaner of the present invention.

FIG. 3 is a table that illustrates an alternative embodiment formulation containing an additional natural cleaner of the present invention.

FIG. 4 is a flow chart that illustrates the manufacturing process of the formulation of the present invention.

FIG. 5 is a table that illustrates a no solvent formulation as taught by the present invention.

FIG. 6 is a table that illustrates an added solvent formulation as taught by the present invention.

FIG. 7 is a table that illustrates a no solvent formulation as taught by the present invention.

FIG. 11 is a table that illustrates an added solvent formulation utilizing a first pairing of specific glucosides where denatured alcohol is the solvent as taught by the present invention.

FIG. 12 is a table that illustrates an added solvent formulation utilizing a first pairing of specific glucosides where acetic acid is the solvent as taught by the present invention.

FIG. 13 is a table that illustrates an added solvent formulation utilizing a third pairing of specific glucosides where glycol ethers are the solvent as taught by the present invention.

FIG. 14 is a table that illustrates an added solvent formulation utilizing a fourth pairing of specific glucosides where acetic acid is the solvent as taught by the present invention.

DETAILED DESCRIPTION OF THE INVENTION

In the following detailed description of the invention of exemplary embodiments of the invention, reference is made

to the accompanying drawings (where like numbers represent like elements), which form a part hereof, and in which is shown by way of illustration specific exemplary embodiments in which the invention may be practiced. These embodiments are described in sufficient detail to enable those skilled in the art to practice the invention, but other embodiments may be utilized and logical, mechanical, electrical, and other changes may be made without departing from the scope of the present invention. The following 10 detailed description is, therefore, not to be taken in a limiting sense, and the scope of the present invention is defined only by the appended claims.

In the following description, specific details are set forth to provide a thorough understanding of the invention. However, it is understood that the invention may be practiced without these specific details. In other instances, well-known structures and techniques known to one of ordinary skill in the art have not been shown in detail in order not to obscure the invention. Referring to the figure, it is possible to see the 15 various major elements constituting the apparatus of the present invention.

The present invention is a formulation for the protection of an automobile or other vehicle or painted surface from bird droppings and other environmental hazards that can 20 have a chemical interaction with a clear coat protective paint layer.

The most common application of the present invention is to cars and other transportation vehicles, which are commonly painted using a base coat/clear coat painting process, 25 where the clear coat is susceptible to chemical interaction with acidic compounds, such as bird droppings and bug remains, resulting in damage to the finish.

Bird droppings are composed out of several main ingredients: uric acid, various organic compounds, water, and a 30 variety of inorganic compounds (salts).

Inorganic compounds, such as salts, can be dissolved and removed by water. This action is empowered by the presence of chelating agent which improves the dissolution of hard or dried dropping to dissolve the salts.

Uric acid itself is only slightly soluble in water or organic 35 solvents. It can be only removed when reacted with a base, converted to a salt, and dissolved.

A study completed by the inventor(s) has shown, unexpectedly, that out of the most popular bases, those which 40 have a larger counter-ion give more soluble salts. Therefore, when considering lithium carbonate, sodium carbonate, and potassium carbonate, the Inventor has found, unexpectedly, that potassium carbonate gives potassium urate, the salt with the highest solubility.

Hydroxides, which can give faster resolution than 45 carbonates, and which might be an obvious or expected solution to the problem solved by the formulation of the present invention, were ruled out due to the fact that hydroxides solutions tend to be corrosive, which would result in damage 50 to a car's clear coat, completely negating the purpose of the present invention in a wipe embodiment.

The remaining organic compounds can be removed either by solvents or surfactants. In the formulation of the present 55 invention, a small amount of organic surfactant was, unexpectedly, found to remove even old and dried bird droppings, which was demonstrated during the tests. The formula of the present invention neutralizes the acid and destabilizes the dropping or marking, making it easy to clean up immediately with one of the surfactants.

Now referring to FIG. 1, a table illustrations the formulation and concentration of each of the compounds in the 60 formulation of the present invention. The formulation is

comprised of the following compounds: Potassium carbonate, Cocoglucoside, a Preservative, Sodium gluconate, and Demineralized water.

In a preferred embodiment, Potassium carbonate is the uric acid remover, and has a concentration of approximately 1-15 percent of the formulation but the percentage can be as high as 25 percent in alternative embodiments.

Cocoglucoside or Coco Glucoside is a natural, non-ionic, surfactant. Like Decyl Glucoside, Cocoglucoside or Coco Glucoside is ultra-mild, and one of the most gentle of the cleansing agents, making it ideal for all foaming and cleansing products. Cocoglucoside, in the formulation of the present invention acts a cleaner and has a concentration of approximately 0.1-20 percent.

A Preservative is a substance or a chemical that is added to products such as food, beverages, pharmaceutical drugs, paints, biological samples, cosmetics, wood, and many other products to prevent decomposition by microbial growth or by undesirable chemical changes. In general, preservation is implemented in two modes, chemical and physical. Chemical preservation entails adding chemical compounds to the product. Physical preservation is not necessary for the formulation of the present invention during manufacturing or to increase or enhance shelf-life of the final product.

A chemical preservative may be added the formulation in any amount or percentage as desired or in any amount or sufficient quantity desired for the preservation or shelf life of the product. The typical amount is 0.01-1 percent. Nothing in the formulation is a subject of visible degradation, so the addition of a preservative to the formulation and any formulation using a preservative is an alternative embodiment to the base formulation, and varying percentages of preservatives and varying preservative compounds are also potential alternative embodiments of the formulation of the present invention.

Sodium gluconate is a compound with formula NaC₆H₁₁O₇. It is the sodium salt of gluconic acid. Sodium gluconate is widely used in textile dyeing, printing, and metal surface water treatment. It is also used as a chelating agent, a steel surface cleaning agent, a cleaning agent for glass bottles, and as a chelating agent for cement, plating, and alumina dyeing industries. It is a white powder that is very soluble in water. In the formulation of the present invention Sodium gluconate is used as a chelating agent and has a concentration of approximately 0.1-15 percent in a preferred embodiment, but can be as high as 25 in alternative embodiments.

Deionized water (DI water, DIW or de-ionized water), often synonymous with demineralized water/DM water, is water that has had almost all of its mineral ions removed, such as cations like sodium, calcium, iron, and copper, and anions such as chloride and sulfate. Deionization is a chemical process that uses specially manufactured ion-exchange resins, which exchange hydrogen and hydroxide ions for dissolved minerals, and then recombine to form water. Because most non-particulate water impurities are dissolved salts, deionization produces highly pure water that is generally similar to distilled water, with the advantage that the process is quicker and does not build up scale. In the formulation of the present invention Demineralized water is used as a solvent and has a concentration of approximately up to 100 percent, with a typical range being 0.1 to 99.7 percent by weight of the formulation.

Additional benefits of the formulation of the present invention are that it is solvent free since it uses Cocoglucoside, a natural, mild, non-ionic, surfactant, instead of a harsh solvent. The formula neutralizes the acid and destabi-

bilizes the dropping or marking, making it easy to clean up immediately with one of the surfactants. In the present invention, the Inventors have disclosed and teach the use of specific surfactants, and are continuing experiments to investigate additional surfactants or combinations and percentages of the compounds which may yield additional, unexpected, better results in neutralization, destabilization, and cleaning.

Additionally, the use of tap water could precipitate insoluble magnesium and calcium carbonates, but the formulation of the present invention specifically requires the use of demineralized water, removing the potential for the creating of such harmful and undesired compounds to form upon application of the formula with bird droppings or other environmental hazards.

Finally, the formulation of the present invention can be certified as organic, due to the specific combination of compounds used.

Now referring to FIG. 2, an alternative embodiment of the present invention is illustrated. In this embodiment, Decyl Glucoside is used in combination with Cocoglucoside, both being cleaners as previously discussed. In this embodiment, the two cleaners can be present in any range of 0.1-15 percent by weight, individually. This alternative embodiment provides an additional cleaning compound and provides additional and alternative chemical reactions for neutralizing bird droppings.

Now referring to FIG. 3, an alternative embodiment of the present invention is illustrated. In this embodiment, Decyl Glucoside is used in combination with Cocobetaine, both being cleaners as previously discussed. In this embodiment, the two cleaners can be present in any range of 0.1-15 percent by weight, individually. This alternative embodiment provides a different combination of cleaners, while providing an additional cleaning compound compared to the main formulation. This embodiment also provides alternative chemical reactions for neutralizing bird droppings compared to the main formulation.

Now referring to FIG. 4, the manufacturing process of the present invention is described in detail. First, a tank must be charged with demineralized water 401. Next sodium gluconate must be added to the demineralized water followed by the addition of one or more preservatives 402. The water, sodium gluconate, and any preservatives must be mixed thoroughly 403. Next, the potassium carbonate is added to the mixture and dissolved while mixing 404. Next the mixing must be slowed to a reduced speed and the cocoglucoside is added 405. Finally, the formulation is mixed slowly to avoid foam formation. 406. Upon complete mixing, the formulation is poured into bottles 407 or the formulation is applied to a roll of wipes to create wet wipes 408.

The product can be delivered to end users or consumers in two formats. The first format is a spray bottle for dispensing the formulation on a surface and then being wiped off with a paper towel, microfiber cloth, or any other fabric. The second formation is for the formulation to be dispensed into wipes, which can be pulled and released in sections. The wipes are soaked with the formulation and can then be applied directly to any surface which his desired to be cleaned or coated.

When the formulation is applied, the potassium carbonate is neutralizing uric acid from bird droppings or other environmental hazards by creating a urate, a soluble salt of uric acid. In this form it is no longer acidic. In chemistry, this reaction is called neutralization.

FIG. 5 is a table that illustrates a no solvent formulation as taught by the present invention. In this embodiment, the drop spray is comprised of: Water 97.016%, Sodium Gluconate 0.1%, Potassium Carbonate 0.124%, Potassium Bicarbonate 0.91%, Sodium citrate 0.1%, Decyl Glucoside 0.1%, Caprylyl Glucoside 0.15%, and a Preservative 1.5%. In this embodiment, the invention is the base formulation, which includes no solvent.

FIG. 6 is a table that illustrates an added solvent formulation as taught by the present invention. In this embodiment a solvent is added to the formulation in a concentration range of 0.05-20%. In this embodiment, the drop spray is comprised of: Water 97.016%, Sodium Gluconate 0.1%, Potassium Carbonate 0.124%, Potassium Bicarbonate 0.91%, Sodium citrate 0.1%, Decyl Glucoside 0.1%, Caprylyl Glucoside 0.15%, Preservative 1.5%, and solvent 0.05-20%.

FIG. 7 is a table that illustrates a no solvent formulation as taught by the present invention. In this no solvent embodiment the formulation is: Water up to 100%, Sodium Gluconate 0.05-5%, Potassium Carbonate 0.05-5%, Potassium Bicarbonate 0.05-5%, Sodium citrate 0.025-5%, two Different Glucosides 0.025-10%, and Preservatives 0.01-5%.

FIG. 8 is a table that illustrates an added solvent formulation as taught by the present invention. In this solvent embodiment the formulation is: Water up to 100%, Sodium Gluconate 0.05-5%, Potassium Carbonate 0.05-5%, Potassium Bicarbonate 0.05-5%, Sodium citrate 0.025-5%, two Different Glucosides 0.025-10%, Preservatives 0.01-5% and a Solvent 0.01-19% which can be comprised of polar or both non-polar and polar solvent compounds.

FIG. 9 is a table that illustrates an added solvent formulation utilizing a first pairing of specific glucosides as taught by the present invention. In this specific glucoside embodiment the formulation is: Water up to 100%, Sodium Gluconate 0.01-5%, Potassium Carbonate 0.05-5%, Potassium Bicarbonate 0.05-5%, Sodium citrate 0.025-5%, Decyl Glucoside 0.025-7%, Caprylyl Glucoside 0.05-7%, Preservatives 0.01-5%, and Solvent 0.01-19%. The two specific glucosides are Decyl Glucoside and Caprylyl Glucoside, which after extensive testing have been chosen in these concentration ranges and specific combination as they yield unexpected and superior test results in comparison to other combinations and percentages which would not be obvious to a person of ordinary skill in the art merely based on known characteristics of such compounds.

FIG. 10 is a table that illustrates an added solvent formulation utilizing a second paring of specific glucosides as taught by the present invention. In this specific glucoside embodiment the formulation is: Water up to 100%, Sodium Gluconate 0.01-5%, Potassium Carbonate 0.05-5%, Potassium Bicarbonate 0.05-5%, Sodium citrate 0.025-5%, Decyl Glucoside 0.025-7%, Coco Glucoside 0.05-7%, Preservatives 0.01-5%, and Solvent 0.01-7%. The two specific glucosides are Decyl Glucoside and Coco Glucoside, which after extensive testing have been chosen in these concentration ranges and specific combination as they yield unexpected and superior test results in comparison to other combinations and percentages which would not be obvious to a person of ordinary skill in the art merely based on known characteristics of such compounds.

FIG. 11 is a table that illustrates an added solvent formulation utilizing a first pairing of specific glucosides where denatured alcohol is the solvent as taught by the present invention. In this specific glucoside and solvent embodiment the formulation is: Water up to 100%, Sodium Gluconate 0.01-5%, Potassium Carbonate 0.05-5%, Potassium Bicarbonate 0.05-5%, Sodium citrate 0.025-5%, Decyl Glucoside 0.025-7%, Caprylyl Glucoside 0.05-7%, Preservatives 0.01-5%, and Denatured Alcohol 0.01-7%.

bonate 0.05-5%, Sodium citrate 0.025-5%, Decyl Glucoside 0.025-7%, Caprylyl Glucoside 0.05-7%, Preservatives 0.01-5%, and Denatured Alcohol 0.01-7%. The two specific glucosides are Decyl Glucoside and Coco Glucoside, which after extensive testing have been chosen in these concentration ranges and specific combination as they yield unexpected and superior test results in comparison to other combinations and percentages which would not be obvious to a person of ordinary skill in the art merely based on known characteristics of such compounds when used in combination with a denatured alcohol solvent solution/formulation.

FIG. 12 is a table that illustrates an added solvent formulation utilizing a first pairing of specific glucosides where acetic acid is the solvent as taught by the present invention. In this specific glucoside and solvent embodiment the formulation is: Water up to 100%, Sodium Gluconate 0.01-5%, Potassium Carbonate 0.05-5%, Potassium Bicarbonate 0.05-5%, Sodium citrate 0.025-5%, Decyl Glucoside 0.025-7%, Caprylyl Glucoside 0.05-7%, Preservatives 0.01-5%, and Acetic Acid 0.01-7%. The two specific glucosides are Decyl Glucoside and Caprylyl Glucoside, which after extensive testing have been chosen in these concentration ranges and specific combination as they yield unexpected and superior test results in comparison to other combinations and percentages which would not be obvious to a person of ordinary skill in the art merely based on known characteristics of such compounds when used in combination with an acetic acid solvent solution/formulation.

FIG. 13 is a table that illustrates an added solvent formulation utilizing a third pairing of specific glucosides where glycol ethers are the solvent as taught by the present invention. In this specific glucoside and solvent embodiment the formulation is: Water up to 100%, Sodium Gluconate 0.01-5%, Potassium Carbonate 0.05-5%, Potassium Bicarbonate 0.05-5%, Sodium citrate 0.025-5%, Lauryl Glucoside 0.025-7%, Decyl Glucoside 0.05-7%, Preservatives 0.01-5%, and Glycol Ethers 0.01-7%. The two specific glucosides are Decyl Glucoside and Lauryl Glucoside, which after extensive testing have been chosen in these concentration ranges and specific combination as they yield unexpected and superior test results in comparison to other combinations and percentages which would not be obvious to a person of ordinary skill in the art merely based on known characteristics of such compounds when used in combination with Glycol Ethers solvent solution/formulation.

FIG. 14 is a table that illustrates an added solvent formulation utilizing a fourth pairing of specific glucosides where acetic acid is the solvent as taught by the present invention. In this specific glucoside and solvent embodiment the formulation is: Water up to 100%, Sodium Gluconate 0.01-5%, Potassium Carbonate 0.05-5%, Potassium Bicarbonate 0.05-5%, Sodium citrate 0.025-5%, Coco Glucoside 0.025-7%, Caprylyl Glucoside 0.05-7%, Preservatives 0.01-5%, and D-Limonene 0.01-7%. The two specific glucosides are Coco Glucoside and Caprylyl Glucoside, which after extensive testing have been chosen in these concentration ranges and specific combination as they yield unexpected and superior test results in comparison to other combinations and percentages which would not be obvious to a person of ordinary skill in the art merely based on known characteristics of such compounds when used in combination with a D-Limonene solvent solution/formulation.

Thus, it is appreciated that the optimum dimensional relationships for the parts of the invention, to include variation in size, materials, shape, form, function, and man-

ner of operation, assembly and use, are deemed readily apparent and obvious to one of ordinary skill in the art, and all equivalent relationships to those illustrated in the drawings and described in the above description are intended to be encompassed by the present invention.

Furthermore, other areas of art may benefit from this method and adjustments to the design are anticipated. Thus, the scope of the invention should be determined by the appended claims and their legal equivalents, rather than by the examples given.

The embodiments of the invention in which an exclusive property or privilege is claimed are defined as follows:

1. An automotive finish protection formulation, the chemical composition comprising:

from about 97.016 by weight percentage demineralized water;

from about 0.1 by weight percentage sodium gluconate;

from about 0.124 by weight percentage potassium carbonate;

from about 0.91 by weight percentage potassium bicarbonate;

from about 0.1 by weight percentage sodium citrate;

from about 0.1 by weight percentage of decyl glucoside;

from about 0.15 by weight percentage caprylyl glucoside;

and

from about 1.5 by weight percentage of a preservative.

2. The chemical composition of claim 1, further comprising

from about 0.05-20 by weight percentage of a solvent.

3. The composition of claim 1, in combination with a spray bottle for application.

4. The composition of claim 2, in combination with a roll of wipes for dispensing and application.

5. An automotive finish protection formulation, the chemical composition comprising:

from about 0.1 to about 99.7 by weight percentage demineralized water;

from about 0.05 to about 5 by weight percentage sodium gluconate;

from about 0.05 to about 5 by weight percentage potassium carbonate;

from about 0.05 to about 5 by weight percentage potassium bicarbonate;

from about 0.025 to about 5 by weight percentage sodium citrate;

5

from about 0.025 to about 10 by weight percentage of a first glucoside;

from about 0.025 to about 10 by weight percentage of a second glucoside;

from about 0.01 to about 5 by weight percentage of a preservative; and

from about 0.01 to about 19 by weight percentage of denatured alcohol as a solvent.

10

6. The chemical composition of claim 5, wherein the first glucoside is decyl glucoside; and the second glucoside is caprylyl glucoside.

7. The chemical composition of claim 5, wherein the first glucoside is decyl glucoside; and the second glucoside is coco glucoside.

8. The chemical composition of claim 5, wherein the first glucoside is decyl glucoside from about 0.025 to about 7 by weight percentage; and the second glucoside is caprylyl glucoside from about 0.05 to about 7 by weight percentage.

9. The chemical composition of claim 5, wherein the first glucoside is decyl glucoside from about 0.025 to about 7 by weight percentage; and the second glucoside is coco glucoside from about 0.05 to about 7 by weight percentage.

10. The chemical composition of claim 2, wherein the solvent is acetic acid.

11. The chemical composition of claim 5, wherein the first glucoside is lauryl glucoside from about 0.025 to about 7 by weight percentage; and the second glucoside is decyl glucoside from about 0.05 to about 7 by weight percentage.

12. The chemical composition of claim 2, wherein the solvent is glycol ethers.

13. The chemical composition of claim 5, wherein the first glucoside is coco glucoside from about 0.025 to about 7 by weight percentage; and the second glucoside is caprylyl glucoside from about 0.05 to about 7 by weight percentage.

14. The chemical composition of claim 2, wherein the solvent is d-limonene.

15. The composition of claim 5, in combination with a spray bottle for application.

16. The composition of claim 5, in combination with a roll of wipes for dispensing and application.
